UNITED STATES PATENT OFFICE.

LOUIS DUNN, OF ST. PAUL, MINNESOTA, ASSIGNOR OF TWO-THIRDS TO EDMUND L. DUNN, OF MILLBOURNE, PENNSYLVANIA, AND ONE-THIRD TO A. V. FABIAN, OF ST. PAUL, MINNESOTA.

TRAIN-STOPPING APPARATUS.

Application filed December 6, 1921. Serial No. 520,266.

To all whom it may concern:

Be it known that I, LOUIS DUNN, a citizen of the United States, residing at St. Paul, in the county of Ramsey and State of Minnesota, have invented certain new and useful Improvements in Train-Stopping Apparatus, of which the following is a specification.

One object of my invention is to provide improved apparatus which will be automatically operative to effect the stopping of a train if the engineer intentionally or unintentionally allows the train to pass a set danger signal.

Another object is to make the apparatus of a practical and durable construction which can be readily installed.

These objects, and other advantageous ends which will be described hereinafter, I attain in the following manner, reference being had to the accompanying drawings in which—

Figure 1 is a fragmentary elevation showing apparatus constructed in accordance with my invention,

Figures 2 and 3 are views of the same general character as shown in Figure 1 illustrating the parts in other positions into which they are moved during the operation of the apparatus to stop a train,

Figures 4, 5 and 6 are enlarged sections taken on the lines 4—4, 5—5 and 6—6 of Figures 1, 2 and 3 respectively,

Figure 7 is an elevation showing a signal device in connection with a trip block which is movable, when the signal device is set, to effect movement of parts of the apparatus to stop a train,

Figure 8 is a view of the same general character as that shown in Figure 7 illustrating said trip block moved into position to effect the stopping of the train,

Figure 9 is a sectional plan view taken on the line 9—9 of Figure 8, and

Figure 10 is a sectional elevation, partly diagrammatic, illustrating apparatus automatically operative to inform a signal operator when an attempt has been made to disregard a danger signal.

Referring to the drawings, 11 represents one rail of a railroad track and 12 represents a semaphore signal device which in the present instance is shown as pivotally mounted at the top of a post 13 which is lo-

cated at the side of the track. A trip block 14 is slidably mounted on the ties 15 of the track and is connected to the signal device 12 by any suitable means. This connecting means, as illustrated, includes a rod 16 which is pivotally connected to the signal device 12 and to a bell-crank lever 17 which is pivotally supported on the post 13. The bell-crank lever is connected to the trip block 14 by a link 18. Thus when the signal device is in the position shown in Figure 7 denoting a clear track, the trip block 14 will be positioned remote from the rail 11 and when the signal device 12 is moved, either automatically or by means such as employed in a signal operating tower, into the position shown in Figure 8, the trip block 14 will be moved into a position close to the rail 11.

Referring particularly to Figures 1 to 6 inclusive, 19 represents a reverse quadrant which may be of any of the usual constructions mounted within the cab of a locomotive; the locomotive cab being diagrammatically represented and indicated at 20; said reverse quadrant is illustrated having notches 21 in its upper surface which are spaced apart in the direction of the length of the quadrant; the reverse lever 22 being pivotally mounted adjacent said reverse quadrant and having a spring-pressed latch 23 adapted, when the reverse lever is swung in either direction from a central neutral position of the lever, to engage within the notches 21 of the quadrant in the usual manner and under ordinary conditions the latch 23 can be removed from the notches by means of a hand grip 24 and when so released the reverse lever will return, under usual conditions, to its central neutral position with respect to the reverse quadrant; the usual reach rod 25 being connected to the reverse lever 22.

In carrying out my invention, I provide an emergency lever 26 which is pivotally supported at 27; said emergency lever having an arcuate or quadrant portion 28 movable in a plane parallel with and closely adjacent one side surface 29 of the reverse quadrant 19 so that when the emergency lever is swung into the position shown in either of Figures 2 and 3, the top surface 105 of the portion 28 will conform to the curvature of the uppermost surface of the reverse quadrant 19 and will be slightly above

the same for a purpose hereinafter described. The latch 23, which is carried by the reverse lever 22, has a portion 31 which projects beyond the side surface 29 of the quadrant 19 so as to be positioned over the top surface 30 of the portion 28. Thus it will be noted that, if the reverse lever 22 is moved out of its central neutral position as shown in Figure 1 and the emergency lever is 10 swung to raise the portion 28 into the position shown in Figure 2, the top edge surface 30 of the portion 28 of the emergency lever will engage and raise the latch 23 out of the notch in the reverse quadrant and the reverse lever will be allowed to move to its central neutral position with respect to the reverse quadrant 19 and again engage within the central neutral notch within the reverse quadrant.

To permit of this latter movement, I provide the portion 28 of the emergency lever 26 with a single notch 32 in its upper surface 30 so that when the reverse lever moves into its central neutral position as shown in Figure 3, the latch will spring into the central neutral notch in the portion 28 of the emergency lever and also into the central neutral notch in the reverse quadrant. It will be further noted that owing to this arrangement the emergency lever will be held in its swung position with the portion 28 raised. The emergency lever 26 has a depending portion 33 which, when the emergency lever is in the position shown in Figure 2, depends to a level below that of the top of the trip block 14 so that if the trip block 14 is moved into the path of movement of the portion 33 during the progress of the train along the track, the portion 33 will strike the trip block and cause the emergency lever to be swung on its pivot 27 to raise the portion 28 with the result above described.

Figures 2, 8 and 9 show the trip block in said latter position with the signal device set as a danger signal with the trip block in its operating position with respect to the emergency lever and Figure 2 shows the latch having been raised out of the notch in which it is located in Figure 1 ready for the return movement of the reverse lever to its central neutral position. Figure 3 shows the reverse lever having moved to its central neutral position with the latch in the central neutral notch of the reverse quadrant and also in the notch 32 of the portion 28 of the emergency lever.

I have illustrated the side rail 34 of the emergency lever provided with connecting members 35, 36, 37 and 38 which may lead to the control throttle, the air brake and sand and cylinder cocks so that, when the emergency lever is swung due to engagement with the trip block, the train will be brought to an emergency stop.

I preferably make the emergency lever of a generally triangular formation and also preferably provide a stop member 39 which can be secured to any supporting structure such for example as the frame 40 of the locomotive; said stop 39 extending between the side rails 34 and 41 of the emergency lever so as to limit the swinging movement of the emergency lever in either direction.

In Figure 10 I have illustrated means operative to inform the signal operator, such for example as the operator in the signal tower or any other person whose business it is to attend to the operation of the signals or to see that the same are observed. This informing or notifying means in the present instance consists of a spring-pressed plunger 42 which is mounted in the trip block 14 and is adapted to be intercepted and moved by the portion 33 of the emergency lever if the locomotive passes the set signal. This plunger 42 is adapted to complete an electric circuit through any enunciating device, such for example as the bell 43 as shown, by closing the electric circuit between two contacts 44 and 45.

Thus by the use of my improved apparatus if the engineer intentionally or unintentionally passes a set danger signal, the train will be automatically stopped or if the engineer should become sick or otherwise incapacitated for the proper control of the train, the train will be automatically stopped upon passing the set danger signal.

While I have specifically mentioned a locomotive and train it will be noted that my invention is applicable to any vehicle passing over the track and having parts similarly operative to those described which result in the stopping of the vehicle since it is obvious that even if a single vehicle such as a locomotive passes a set signal the vehicle will be stopped.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. The combination with a locomotive having a reverse lever and means for holding the reverse lever out of neutral position, of stopping apparatus having a portion operative to cause said first means to allow said first lever to return to its neutral position; substantially as described.

2. The combination with a locomotive having a reverse lever and means for hold-

ing the reverse lever out of neutral position, of stopping apparatus having a portion operative to cause said first means to allow said first lever to return to its neutral position, said apparatus having a part operative to effect the stopping of the locomotive; substantially as described.

3. The combination with a locomotive having a reverse lever and means for holding the reverse lever out of neutral position, of stopping means for moving said first means out of holding position to allow said reverse lever to return to its neutral position; substantially as described.

15 4. The combination with a locomotive having a reverse quadrant provided with notches, a reverse lever, and a latch carried by said reverse lever for holding engagement within said notches when the reverse lever is moved out of neutral position, of stopping apparatus including a portion movable to move said latch out of said holding position and allow the reverse lever to return to its neutral position; substantially as described.

20 5. The combination with a locomotive having a reverse quadrant provided with notches, a reverse lever, and a latch carried by said reverse lever for holding engagement within said notches when the reverse lever is moved out of neutral position, of stopping apparatus including a portion movable to move said latch out of said holding position and allow the reverse lever to return to its neutral position, said portion having a notch therein in which a portion of said latch can enter when said lever returns to its neutral position; substantially as described.

25 6. The combination with a locomotive having a reverse lever and means for holding the reverse lever out of neutral position, of signal operated tripping means; and stopping apparatus having a portion operative, due to engagement with said tripping means, to cause said first means to allow said reverse lever to return to its neutral position; substantially as described.

7. The combination with a locomotive having a reverse quadrant provided with notches, a reverse lever, and a latch carried by said reverse lever for holding engagement with said notches when the reverse lever is moved out of neutral position, of stopping apparatus including an arcuate portion operative to move said latch out of said holding position and allow said reverse lever to return to its neutral position, said arcuate portion serving as guiding means to

keep said latch free of the notches of said quadrant during said movement of the lever to its neutral position; substantially as described.

8. The combination with a locomotive having a reverse quadrant provided with notches, a reverse lever, and a latch carried by said reverse lever for holding engagement with said notches when the reverse lever is moved out of neutral position, of stopping apparatus including an arcuate portion operative to move said latch out of said holding position and allow said reverse lever to return to its neutral position, said arcuate portion serving as guiding means to keep said latch free of the notches of said quadrant during said movement of the lever to its neutral position, said arcuate portion having a notch to allow said latch to enter therein and to enter the neutral notch of the quadrant when the lever has returned to its neutral position; substantially as described.

9. The combination with a locomotive having a reverse quadrant provided with notches, a reverse lever and a latch carried by the lever for holding engagement with the notches when the line is moved out of neutral position, of stopping apparatus including a lever consisting of diverging arms connected by an arcuate element operative to move the latch out of holding position and allow the reverse lever to return to its neutral position, the arcuate element serving as guiding means to keep the latch free of the notches during the movement of the lever to neutral position, and means for limiting the movement of the arcuate lever, substantially as described.

10. The combination of a railway signal device; a signal-operated tripping device located adjacent a track; stopping mechanism on a vehicle adapted to move over the track, the stopping means including a member adapted, when the signal is set for stopping, to engage and be actuated by the tripping device, and means, rendered operative by said member for informing the signal operator in case the vehicle passes a signal set for stopping, substantially as described.

In testimony whereof I have signed my name to this specification in the presence of two subscribing witnesses.
